PROTECTIVE DEVICE FOR APPARATUS SUBJECT TO FIRE HAZARD

Filed April 16, 1928

UNITED STATES PATENT OFFICE

CHARLES C. WHITTAKER, OF PITTSBURGH, PENNSYLVANIA, ASSIGNOR TO WESTINGHOUSE ELECTRIC & MANUFACTURING COMPANY, A CORPORATION OF PENNSYLVANIA

PROTECTIVE DEVICE FOR APPARATUS SUBJECT TO FIRE HAZARD

Application filed April 16, 1928. Serial No. 270,185.

My invention relates to protective devices and more especially to means for decreasing the fire hazard of electric-locomotive transformers.

5 My invention resides in automatic means for disconnecting electrical apparatus from its supply circuit and immersing said apparatus in a fire-quenching medium in the event of fire therein.

10 It is characteristic of my invention that it is particularly applicable to electric-locomotive service wherein, in the event of fire in a tunnel, the great volume of smoke incident thereto, which frightens passengers, is prevented.

15 It is further characteristic of my invention that the apparatus associated therewith is protected from serious damage because of fire arising from short circuits and grounds.

20 In a particularly desirable application of my invention, in electric locomotives, it is customary to transform the electric energy necessary to operate the motors from a relatively high voltage on the trolley to a voltage suitable for the motors by a transformer mounted in the locomotive itself. Such

25 transformers are disposed in a chamber through which a cooling blast of air is continually circulated for removing the heat generated by the transformer and maintaining its temperature below a predetermined maximum value.

30 The high-voltage primary windings of such transformers have one terminal connected to the trolley and the other terminal connected to ground. Sometimes, due to age, vibration and unavoidable circumstances, breakdowns and failures occur in the insulation between the windings and ground.

35 Such failures cause arcing which results in rapid combustion of the insulating material and increase in temperature accompanied by large volumes of smoke, which is fanned by the cooling air blast mentioned above.

40 I provide means for protecting such ap-

paratus from fire in the event of such short circuits and also provide means for preventing the production of the large volumes of smoke mentioned above. More specifically, I provide means for disconnecting the 50 transformer from its supply circuit, means for stopping the cooling air blast, and means for immersing the transformer in a fire-quenching medium, automatically, in the event of a temperature exceeding a predetermined maximum valve in the chamber 55 housing the transformer.

For a specific embodiment of my invention, reference may be had to the accompanying drawing taken in connection with 60 the following description.

In the drawing:

Fig. 1 is a view, in front elevation, partially in cross section, of a locomotive transformer disposed in a chamber.

Fig. 2 is a view, in side elevation, of the device shown in Fig. 1, with the addition of my improvement.

Fig. 3 is an enlarged view, in elevation, of the valve and mechanism for opening the 70 same shown in Fig. 2,

Fig. 4 is an enlarged view, in elevation, of the relief valve shown in Fig. 1 for permitting the air in the chamber to be exhausted by the fire-quenching medium.

Fig. 5 is a bottom plan view of the valve shown in Fig. 4, and

Fig. 6 is a view similar to Fig. 2 of an electrical modification of means for opening the valve of the fire-quenching container.

In normal operation, the transformer 1, comprising a core 2 and coils 3, is energized by the electrical energy derived from the trolley wire (not shown) through a conductor 4, that conveys current to a terminal 85 bushing 5 mounted on a casing 6. A blower 7 supplies air, under pressure, to the casing 6 through a pipe 8 which flares out to the width of the casing 6 and furnishes air to the whole opening 9. As indicated by the 90

arrows, the air from the blower 7 circulates throughout the chamber 6, reduces the temperature of the transformer 1 and is blown out of the opening 10.

5 As pointed out above, in case of a short circuit, the consequent burning of the insulating material was aided by the air blast from the blower 7, and large volumes of smoke were emitted from the opening 10 to the discomfiture and annoyance of passengers, especially in tunnels.

To avoid such annoyance and to protect the transformer 2 from damage, I provide means for disconnecting the conductor 4, 15 shutting down the blower motor 7a, closing the openings 9 and 10, and flooding the casing 1 with a fire quenching medium such as carbon dioxide gas when a predetermined maximum temperature is exceeded.

20 To this end, a heat-fusible link 11 is associated with the apparatus to initiate the operation of my device in the event of a temperature exceeding a predetermined maximum value. A preferable arrangement, as 25 indicated in the drawing, comprises providing the openings 9 and 10 with doors or latches 12 and 13, respectively. The doors 12 and 13 are linked together by a rod 14 that is pivoted at its ends to arms 15 and 16 30 which are, in turn, rigidly secured to the axes 17 and 17' of the doors 12 and 13, respectively. The fusible link 11 is connected between a bracket 18 mounted on the casing 6 and the door 13. The link 11 holds 35 the doors 12 and 13 in open position against the force of a spring 19 that is adapted to exert a force always tending to close these doors. The axis 17 is provided with a drum 20 mounted on one end. The drum 20 is 40 provided with conducting segments 21 and 22 that are associated with contacting fingers 23 and 24, and 25 and 26, respectively.

A turning of the drum 20 is adapted to disconnect the conductor 4 by operating a 45 circuit breaker 27 that is in the circuit of the conductor 4.

The circuit breaker 27 comprises the usual toggle 28 that is held in closed position by an electromagnet 29, against the force of a spring 30. The electromagnet 29 is energized from a suitable electrical source of supply (not shown) through conductors 31, 32, 33 and 34. A switch 35 is provided in the circuit of the conductor 32 for manually operating the circuit breaker 27. Normally, the electromagnet 29 is energized and the transformer 1 is in circuit, however, when the drum 20 is rotated, the conducting segment 22 is moved from under the contacting fingers 25 and 26, and the energizing circuit of the electromagnet 29 is broken, thereby permitting the spring 30 to open the breaker 27 and disconnect the circuit of the conductor 4 and the transformer 1, putting the latter out of operation.

In a similar manner the blower motor 7a is energized from the electrical source of supply through conductors 31, 36, 37 and 34 that are connected in circuit relation through the conducting segment 21 on the drum 20 and contacting fingers 23 and 24. A rotation of the drum 20 disconnects the circuit from the source of supply to the blower 7 and causes a discontinuance of the supply of cooling air to the casing 1.

The other end of the axis 17 of the doors 12 and 13 is provided with an arm 38 that is, in turn, connected to a link 39 that has a slot 40 near one end. The arm 38, when turned by the axis 17, opens the valve 41 of a tank 42 containing a fire-quenching medium, such as carbon dioxide gas, and permits the latter to fill the chamber through a connecting pipe 43. The handle 44 of the valve 41 is loosely connected to the link 39 in the opening 40 so that the doors 12 and 13 will be almost closed before the lost motion due to the opening 40 is taken up and the valve 41 snapped open.

When the blower 7 is stopped and the doors 12 and 13 are closed, the chamber 6 is still filled with air. To provide for the proper displacement of such air by the carbon-dioxide gas, I place a valve 45 in the upper part of the casing 6 so that, as the carbon dioxide gas enters at the bottom of the chamber, the air is exhausted by way of the valve 45.

The valve 45 preferably comprises a disc 46 that fits snugly against the surface of the casing to prevent the cooling air from escaping through an opening 47 in the latter. The air from the blower 7 causes a pressure of about 3 or 4 ounces in the chamber which is sufficient to hold the disc 46 tight against the surface of the casing. However, when the blower 7 stops and the doors 12 and 13 are closed, the pressure within the tanks falls which permits gravity to pull the disc 46 away from the wall near the opening 47 to the supporting fingers 48 that are secured to the wall 49. In such position, the air that is displaced by the carbon dioxide gas flows out of the opening 47.

When a predetermined temperature of the air surrounding the fusible link 11 is exceeded, the latter melts and the spring 19 quickly forces the doors 12 and 13 closed. At the same time, the drum 20 rotates and disconnects the blower motor 7a and operates the circuit breaker 27 which disconnects the transformer winding from its source of supply. The rotation of the shaft 17 also opens the valve 41, and the chamber 6 is filled with carbon dioxide gas, the air being exhausted through the valve 45. The closing of the doors 12 and 13, together with the flooding of the casing 1 with carbon dioxide gas, effectually quenches any tendency toward combustion of the insulat-

ing material of the transformer 1. The closing of the doors 12 and 13, at the same time, prevents the emission of any smoke. The apparatus is, therefore, fully protected 5 against damage.

In Fig. 6, I show a modification of the method of operating the valve 41 by electrical means instead of mechanical means. In such modification, the drum 20 may be 10 provided with a third conducting segment 50 which operates to disconnect an electrical circuit through contacting fingers 51 and 52 when the drum 20 is rotated by the spring 19. The valve 41, in such case, would 15 comprise the well-known magnet-operated plunger type connected to a source of supply (not shown) through conductors 53 and 54 and the conducting segment 50 on the drum 20. A rotation of the drum 20 causes 20 an operation of the valve 41 to fill the casing 6 with carbon dioxide, in a manner somewhat similar to that outlined above in connection with a mechanically operated valve.

My invention is applicable to apparatus 25 other than that described above and I, therefore, wish to be limited only within the scope of the appended claims.

I claim as my invention:

1. In a locomotive transformer disposed 30 in a casing and subject to fire hazard, the combination with means, including a circuit breaker, for disconnecting said transformer from its supply circuit, and means for venting the atmosphere surrounding said transformer from said casing and introducing carbon dioxide gas in the event of fire in 35 said transformer.

2. In combination, a casing housing apparatus subject to fire, means for circulating 40 air through said casing for cooling said apparatus, means for stopping said circulation of air, and means for venting air from said casing and flooding said casing with a fire-quenching medium in case of fire in said apparatus.

3. In combination, a casing, means for circulating air through said casing, and means for stopping said air circulation and displacing the air within said casing with 50 a fire-quenching medium when a predetermined temperature is exceeded in said casing.

4. In combination, an electrical transformer, a casing for said transformer, automatic means responsive to the temperature within said casing for flooding said casing with an air-free fire-quenching gas in the event of a ground or short circuit in said transformer, and venting means arranged to 55 vent the gases displaced by said fire-quenching gas.

5. In combination, electrical apparatus, a casing enclosing said apparatus, means for forcing a fluid through said casing to maintain the temperature of said apparatus be-

low a predetermined maximum value, means for stopping said temperature-maintaining means and means, actuated upon the temperature of said apparatus exceeding said maximum value, for venting said fluid from 70 the casing, and means for introducing an inert gas that will not support combustion into the casing.

6. In combination, a transformer, means for housing said transformer, means for 75 circulating air through said housing means, means actuated upon the temperature of said housing means exceeding a certain value, for stopping the circulation of said air and means for venting the remaining air and 80 introducing a gas having the fire-preventative properties of carbon dioxide.

In testimony whereof, I have hereunto 85 subscribed my name this 12th day of April 1928.

CHARLES C. WHITTAKER.
